UNITED STATES PATENT OFFICE.

LUCIUS WOODRUFF, OF BINGHAMTON, NEW YORK.

DESIGN FOR A WHIP-HOLDER.

SPECIFICATION forming part of Design No. 30,882, dated May 30, 1899.

Application filed April 28, 1899. Serial No. 714,916. Term of patent 7 years.

To all whom it may concern:

Be it known that I, LUCIUS WOODRUFF, a citizen of the United States, residing at Binghamton, in the county of Broome, in the State of New York, have invented and produced a new and original Design for Whip-Racks, of which the following is a specification, reference being had to the accompanying drawings, forming a part thereof.

Figure 1 is a top plan view. Fig. 2 is a bottom plan view. Fig. 3 is a transverse section on line X X in Fig. 1.

As shown in the drawings, the leading or material feature of my design consists in a concavo-convex body curved longitudinally, having the general form of a segment of a circle and having notches upon its lateral edges tapering inwardly.

a is the body, and *b* are the inwardly-tapering notches. The edges of the notches upon the lower surface are chamfered off, as shown in Fig. 2.

Having described my invention, what I claim, and desire to secure by Letters Patent, is—

The design for a whip-rack, substantially as herein described and shown.

In witness whereof I have hereunto set my hand this 11th day of April, 1899.

LUCIUS WOODRUFF.
